UNITED STATES PATENT OFFICE.

FREDERICK C. OVERBURY, OF HILLSDALE, NEW JERSEY, AND CHESTER E. RAHR, OF BROOKLINE, MASSACHUSETTS, ASSIGNEES TO THE FLINTKOTE COMPANY, OF BOSTON, MASSACHUSETTS, A CORPORATION OF MASSACHUSETTS.

ASPHALT PACKAGE AND METHOD OF MAKING THE SAME.

1,391,969.

Specification of Letters Patent. Patented Sept. 27, 1921.

Application filed May 8, 1918, Serial No. 233,267. Renewed March 9, 1921. Serial No. 450,937.

To all whom it may concern:

Be it known that we, FREDERICK C. OVERBURY and CHESTER E. RAHR, citizens of the United States, residing, respectively, at 5 Hillsdale, in the county of Bergen and State of New Jersey, and at Brookline, in the county of Norfolk and State of Massachusetts, have invented new and useful Improvements in Asphalt Packages and Methods of 10 Making the Same, of which the following is a specification.

This invention has for its object to provide for the packaging of asphalt or like solidifying substances for shipment, so as 15 to obviate the use of metal drums or barrels which have heretofore been regarded as essential. The use of such containers ordinarily results in a comparatively large loss and wastage due to the adherence of the 20 asphalt or pitch to the interior surfaces thereof, and entails an increased cost to the consumer on account of the cost of the container, the increased charges for transportation because of the weight thereof, and the 25 labor in removing the material from the container and handling the latter.

In accordance with the present invention, the asphalt, pitch or like material, which solidifies on cooling to ordinary temperatures, is poured while in molten condition into an envelop consisting of flexible fibrous sheet material and permitted to cool and solidify. The asphalt adheres to the envelop and is covered and protected thereby, and a 30 package is thus formed which may be shipped to the consumer. We have found that, although paper may be employed for this purpose, yet, to secure the best results and to save wastage, the paper should be 35 waterproofed, and should be coated with a high-melting-point pitch or asphalt or equivalent substance on the side which comes into contact with the material to be protected thereby. An envelop thus formed may 40 be subsequently stripped from the solidified contained mass without difficulty, the coating fusing, as it were, with the body of the asphalt, so that the sheet, on being stripped from the mass, comes away clean. As the paper, because of its flexibility and lack of tensile strength, is incapable of withstand- 45 ing the hydrostatic pressure of the molten material when the latter is being introduced into the envelop, it is desirable to employ a

mold into which the envelop may be located 55 as a lining. This mold is preferably made in such manner as to provide for the radiation of the heat of the molten pitch or asphalt to insure its rapid cooling and solidification, and consequently it may be formed 60 of woven wire or perforated sheet metal, in such wise that it can be removed from the package when desired. For example, a sheet of metal or woven wire, suitably braced, may be formed into a tube or cylinder, and the 65 ends of the sheet temporarily connected by clamps to form a mold, into which the envelop is introduced, so that, when the pitch or asphalt has been poured therein and has 70 solidified, the mold or receptacle may be removed, leaving the envelop sticking to the solidified mass. If desired, the mold may be provided with a central core, so that the solidification of the mass will be expedited.

On the drawings,

Figure 1 illustrates an openwork knock-down form or mold, with the paper envelop therein ready to receive the molten asphalt.

Fig. 2 represents a plan view of the same.

Fig. 3 represents a package of asphalt.

Fig. 4 represents another package having hoops, and shows a portion of a form with the ends secured together with twisted wire.

Fig. 5 shows, in plan view, a portion of the form, and illustrates how the form may be closed temporarily by means of twisted wire.

Fig. 6 shows one way in which the bottom of the form may be made.

Fig. 7 illustrates a form containing asphalt, in which there is a central removable core.

Fig. 8 illustrates conventionally a piece of the envelop.

Referring to the drawings,—a form or 95 mold is indicated in Fig. 1, which consists of a sheet of woven wire 10, say half inch mesh, which is bent into cylindrical form, and which is braced at its selvages and at its ends with straps or wire rods 11, 12, to 100 give it the necessary strength. Clamps 13 of any suitable construction are employed for clamping the ends of the sheet together, or, if desired, the ends of the sheet may be secured by stove wire, as at 13, Fig. 5, which 105 easily may be cut to permit the removal of the form. The lower end of the form is closed by a head, 14, of any suitable ma-

2

terial, such as wood for example. The envelops may be made of paper initially prepared in the shape of a bag having an open upper end, which can be inserted in the 5 form, but this is not necessary as it may be formed of separate parts. For example, a circular sheet of paper 15 may be placed at the bottom of the form with its edge upturned as at 115, and then an elongated 10 sheet 16 may be introduced into the form as a lining for the cylindrical body portion thereof and its ends brought out and clamped together by the end braces 12 and the clamps 13, as shown in Fig. 2. The lower edges of 15 the sheet 16 are nested within the upturned edge or flange of the bottom sheet 15. A small quantity of the material to be shipped now may be poured into the lined form, up to the level indicated by the line α — α and permitted to 20 set at the juncture of the side and bottom linings, and then the remainder of the molten material may be poured into the form and permitted to solidify. As soon as 25 the solidification has occurred, the wire form may be removed, leaving the envelop inclosing and adhering to the side and end of the molded mass. While the mass is still plastic, a circular sheet of paper may be 30 pressed upon the upper end thereof, if desired.

The envelop is preferably formed of paper 17, as shown conventionally in Fig. 8, which may be either Kraft or Manila or the like, 35 impregnated with an asphaltic or other suitable waterproofing composition, and having a coating or layer 18 of high-melting-point pitch or asphalt. Of course, instead of paper some other suitable flexible material 40 may be used, but we think that a fairly strong paper is the best, because of the ease with which it may be stripped from the molded asphaltic mass. From our observation, it would appear that, when the hot 45 molten asphalt is poured into the asphalt-coated envelop, the coating is melted and fuses therewith, and on cooling sets therewith, so that, on stripping the paper from the molded mass, the asphalt is left on the 50 mass, the paper coming away comparatively clean. The presence of the coating prevents the paper from being burned by the molten asphaltic mass on the introduction of the latter into the envelop.

55 We sometimes find it convenient to leave the form on the molded and enveloped mass and thus to ship it, where the package may be subjected to extraordinarily rough usage. The consumer has no difficulty in removing 60 the form and returning it with others in a flat package or in a roll form, the relative flexibility of the material of which the form is made permitting it to be bent into a flat sheet or to be nested together with others.

65 Of course, after illustrating one way in

which the invention may be practised, various changes and refinements will readily suggest themselves to those skilled in the art. For example, a frusto conical core 19 of perforated or foraminous material may 70 be placed in the form and covered with a layer 20 of the treated paper, and, after the asphaltic mass has solidified, the core may be withdrawn. By the use of the core, the radiation of heat is increased and the mass 75 more rapidly solidified. Again, if desired, hoops 21 may be introduced into the form before the envelop or lining is introduced to protect the ends of the package, or upright strips 22 may be placed inside the lining. 80 In the first case, the internal pressure causes the paper to bulge slightly between the hoops so that they are held in place when the mass solidifies.

We secure a decided advantage by using 85 waterproof paper, because, after the molten asphalt has been poured into the mold or form, the package can be sprayed with water, or passed while on trucks through a shower of water to hasten the solidification 90 of the plastic mass, without detriment to the envelop, and of course the package can be exposed to the weather without injury to the paper.

Naturally, instead of employing as the 95 bottom of the form a head made of wood, it may be made of stout wire cloth as shown at 23, braced with stiffeners 24, the ends of which form projections or fingers for entering the meshes of the side of the form and 100 holding the head in place.

The package can be produced to best advantage in connection with pitch or asphalt having a relatively high melting point, say 200° F. or above, but compounds having a 105 much lower melting point can be packaged if desired, so long as they do not soften too much when exposed to solar heat, and in such case the wire form is left on, for shipment. The envelop may be coated with material identical with that to be packaged, but, for all general purposes, we prefer a high-melting-point blown asphalt for the purpose. The waterproofing compound with which the paper is impregnated may 115 be similar to that used in making commercial prepared roofing.

Various changes may be made in both the method and package herein described without departing from the scope of the invention defined in the claims, in which it will be understood that the words "asphaltic material" are intended to include pitch, tar and other like compositions which solidify on cooling to ordinary atmospheric temperatures.

What we claim is:—

1. A method of packaging asphaltic material, which consists in introducing a flexible sheet of wrapping material into, and as 130

- the lining of, a removable form, clamping the meeting edges of such sheet, and then molding said asphaltic material in said form and envelop. 45
5. 2. A method of packaging asphaltic material, which consists in introducing into, and as the lining of, a removable form, a flexible fibrous material coated with a suitable material, and molding said asphaltic material in said envelop. 50
10. 3. A method of packaging asphaltic material, which consists in introducing a flexible fibrous envelop into, and as the lining of, a removable form, then molding said asphaltic material in said form and envelop, and removing said form, leaving the envelop adhering to the molded mass. 55
15. 4. A method of packaging asphaltic material, which consists in introducing into, and as the lining, of a removable form, a sheet of flexible fibrous material coated with an adhesive, clamping the meeting edges of said sheet, molding said asphaltic material in said envelop, and removing said form leaving the envelop adhering to the molded mass. 60
20. 5. A method of packaging asphaltic material, which consists in lining a metallic form with an envelop of flexible sheet material having an internal surface coated with asphaltic material, introducing the asphaltic material, to be packaged, in molten condition into the said envelop, and permitting said mass of asphaltic material to solidify, and adhere to the coated face of said lining. 65
25. 6. A method of packaging asphaltic material, which consists in forming a wrapper of flexible material coated with an asphaltic composition into a tubular receptacle within a hollow mold, filling said receptacle with molten asphalt, permitting the latter to fuse 70
30. 7. A method of packaging asphaltic material, which consists in bending a sheet of flexible fibrous material into tubular form, confining the same within a tubular mold and clamping the meeting edges of said sheets together, filling said tube with molten asphalt and permitting the latter to cool and to adhere to said tube, and then removing said mold, leaving said cooled mass and the adherent wrapper in marketable condition. 75
35. 8. A method of packaging asphaltic material, which consists in bending into tubular form a flexible fibrous wrapper having an inner layer of asphaltic composition, inclosing said wrapper within a tubular mold and clamping the meeting edges of said wrapper together, filling the wrapper with molten asphalt, fusing together the said material and said asphaltic layer, permitting said material to cool and set, and removing said mold. 80
40. 9. A method of packaging asphaltic material, which consists in bending a wrapper of flexible material into tubular form, locating a bottom formed of such material at the lower end of the tube, inclosing the envelop so formed within a removable mold, filling said tube with molten asphaltic material, permitting the same to adhere to said wrapper end bottom and to cool, and then removing said mold. 85

In testimony whereof we have affixed our signatures.

FREDERICK C. OVERBURY.
